UNITED STATES PATENT OFFICE.

FLOYD L. SCOTT, OF HOUSTON, TEXAS, ASSIGNOR TO HUGHES TOOL COMPANY, OF HOUSTON, TEXAS, A CORPORATION OF TEXAS.

SUPPORT FOR REAMER CUTTERS.

Application filed February 4, 1928. Serial No. 251,817.

My invention relates to reaming cutters employed in well drilling, and is particularly concerned with the manner of mounting the cutter pins in the reamer head.

5 It is a common custom, in mounting reamer cutters in a drill head, to place the cutters in pockets in the side of the drill head formed between the two meeting faces of the two sections into which the drill is 10 divided. The difficulty arising from this method lies in the fact that it is practically impossible to support the ends of the cutter pins between the meeting faces of the head so that there will be no looseness or play in 15 the pins.

It is an object of the invention to provide a secure means of mounting the reamer cutters in a bit head where the head is longitudinally divided into a plurality of parts.

20 It is desired that the cutter pins be firmly supported at both ends and that they also be held against rotation during the operation of the tool.

Referring to the drawings herewith, Fig. 25 1 is a side elevation of a well drill in which my supporting structure is embodied.

Fig. 2 is a transverse section taken on the plane 2-2 of Fig. 1.

The reamers here shown are employed in 30 the head of a well drill of common construction. The head 1, is longitudinally divided into two parts. When assembled the head is of a generally cylindrical form but has channels or grooves 2, in the outer periphery 35 to allow passage of flushing fluid and cuttings. Drill cutters 3, are mounted on the forward or lower end to cut the well bore. The upper end of the head is screwed within a drill collar 4, and through bolts 5, secure 40 the halves of the head adjacent the lower end.

The reaming cutters are mounted in pockets 8, formed in the meeting sides of the head. There are preferably two sections to 45 the cutter, a lower section 6, tapered at its lower end and an upper section 7, approximately cylindrical in shape.

Each set of cutters is mounted upon a pin 9. To receive said pin one half 10, of 50 the head 1, has bosses 11 and 12, formed on its flattened face at the upper and lower sides respectively of the recess 8, for the cutters. Said bosses are rounded on their lateral faces in this embodiment (see Fig. 2) 55 and the other half of the head is recessed

to receive them. Said bosses are formed with aligned openings to receive the cutter pin 9 together with ring shaped bushings 13, around the ends of the pin.

To introduce the cutter pins into position 60 in these bearings, I groove or channel the face of the section 10, of the head below the openings in the lower boss as shown at 14 in dotted lines in Fig. 1. Thus when the halves of the head are taken apart, the 65 reamer cutters may be laid in the recess 8, and the cutter pin may be introduced through the cutters by placing said pin in the groove 14, and moving it longitudinally through the bushing and the cutters against 70 the shoulder 16, at the upper end of the boss 11. The lower end of the pin 9, is cut away on one side to form a shoulder 17, to abut against the shoulder on the head below 75 the boss 12.

It will be noted that the cutters may be quickly and easily mounted on their pins and when the two halves of the head are fitted together the pins will be firmly supported. The forming of the upper and lower bearings for the pins in bosses integral with the head will prevent play of the pins where the halves of the head wear, and the means of holding the cutter pins in position by contact of the ends of the pins with parts of the 80 reamer head assures that the pins and cutters will not become loose or get lost in the hole.

Having thus described my invention, what I claim as new is:

1. A reamer including a head longitudinally divided into a plurality of sections, said sections being formed with cutter pockets in their meeting faces, laterally projecting bosses formed on one of said sections interfitting within recesses on the adjacent section at the upper and lower ends of said 85 pockets, cutter pin bearings in said bosses, pins in said bearings, and cutters on said pins.

2. A reamer including a head longitudinally divided into a plurality of sections, said sections having registering recesses in their meeting faces to receive rotating cutters, bosses on one end of said sections at the upper and lower ends of said recesses, bearings formed in aligned openings in said bosses, cutter pins adapted to fit within said bearings, means on said head to hold said pins in position when said head is assembled, and cutters on said pins.

3. A reamer including a head longitudinally divided into a plurality of sections, said sections having registering recesses in their meeting faces to receive rotating cutters, bosses on one of said sections at the upper and lower ends of said recesses, bearings formed in aligned openings in said bosses, cutter pins adapted to fit within said bearings, a shoulder on one of said sections 10 above the upper boss and a second shoulder formed on the adjacent section below the lower boss against which said pin may contact when said head is assembled, and cutters on said pins.

4. In a reamer including a head longitudinally divided into a plurality of sections, cutters mounted in pockets in the meeting faces of said sections, pins upon which said cutters are rotatable, supported at their ends in bosses integral with one of said sections, and shoulders formed on said head adapted to bear against the ends of said pins when said head is assembled to retain said pins against longitudinal movement.

In testimony whereof, I hereunto affix 25 my signature this 25th day of January, A. D. 1928.

FLOYD L. SCOTT.
